Primary Examiner — Mitchell I. Siegel*(74) Attorney, Agent, or Firm* — Harness, Dickey & Pierce, P.L.C.(57) **CLAIM**

The ornamental design for a golf putter grip, as shown and described.

DESCRIPTION

FIG. 1 is a side view of the golf putter grip attached to an unclaimed golf putter and shaft;

FIG. 2 is an enlarged perspective of the golf putter grip;

FIG. 3 is a front elevational view of FIG. 2;

FIG. 4 is a rear elevational view of FIG. 2;

FIG. 5 is a top plan view of FIG. 2;

FIG. 6 is a bottom plan view of FIG. 2;

FIG. 7 is a right side elevational view of FIG. 2; and,

FIG. 8 is a left side elevational view of FIG. 2.

The broken line showing of the putter head, shaft and top and bottom surfaces of the golf putter grip is included for the purpose of illustrating unclaimed subject matter and forms no part of the claimed design.
